UNITED STATES PATENT OFFICE

CHARLES W. MCKINLEY, OF FLINT, MICHIGAN, ASSIGNOR TO A C SPARK PLUG COMPANY, OF FLINT, MICHIGAN, A COMPANY OF MICHIGAN

OIL FILTER BY-PASS

Application filed April 2, 1927. Serial No. 180,542.

This invention relates to oil filters for internal combustion engines used on automotive vehicles.

The object of the invention is to construct a novel oil filter by-pass which will function so as to allow the oil to flow back to the working parts when the filter becomes clogged, or for some other reason will not allow the oil to flow thereto. The by-pass has a valve mechanism which is automatically acting and which will be brought into operation only when the filter refuses to function.

The automatically acting valve of the present invention is elongated and rectangular and has a ball end to conform to rounded seat in the by-pass. This valve is spring pressed against its seat and when the filter refuses to work the circulating oil will press against the valve and force it off its seat so as to allow the oil to circulate back to the working parts of the engine without passing thru the filter.

The by-pass arrangement of the present invention is provided with a test valve in order to ascertain whether the filter is clogged. This test valve operates on the spring pressed valve to hold it against its seat while an auxiliary conduit thru the center of the test valve is used to ascertain whether the oil is flowing thru the filter.

The invention is disclosed in the accompanying drawings in which:

Figure 1 is a view of a portion of an oil filter necessary to illustrate my invention, with parts shown in section.

Figure 2 is a section on line 2—2 of Figure 1.

Figure 3 is a perspective view of the spring pressed valve of my invention.

Figure 4 is an enlarged detailed sectional view of line 4—4 of Figure 2.

Referring to the numbered parts on the drawings 10 is the filter and 11 the cover thereof, while 12 indicates the by-pass or bracket of the invention as a whole. The filter is provided with the usual inlet and outlet pipes 13 and 14 respectively which lead into the inlet and outlet openings 15 and 16 in the by-pass 12.

The cover 11 is provided with headed

studs 17 which project upwardly into the openings 15 and 16 and to these studs there are secured plugs 18 having flange heads 19 for closing the upper portion of the openings 15 and 16. Washers 20' are provided between heads 18 and the by-pass 12 to insure a liquid tight contact. The studs 17 and plugs 18 are provided with concentric bores or passages 20 and the plug 18 is further provided with radial openings 21 leading from the passage 20 to an annular groove 22 in a plug 18.

To allow for direct intercommunication between the inlet and outlet ports 15 and 16 respectively I provide a passageway 23 comprising the conduit 24 leading from the inlet plug 18 and a conduit 25 leading from the conduit 24 to the outlet plug 18. Within the conduit 24 there is placed the by-pass valve 26 which is elongated and rectangular in form and has a ball end 27 which rests on a correspondingly shaped seat 28 in the by-pass. While I have shown and prefer the elongated rectangular valve, it is obvious that a ball or poppet valve may be used just as well. The valve is hollow as shown at 29 and receives therein a coil spring 30 the upper end of which presses against a test valve having a head 31 on a sleeve 32 having a handle 33, threaded at 34 into a plug 35 which in turn is threaded at 36 into an opening 37 of the by-pass 12. The sleeve 32 is hollow as indicated at 38 and has openings 39, preferably two in number, at its innermost portion the purpose of which will be later described. In case a ball or poppet valve is used the head 31 will preferably have an extension to guide the spring 30.

From an inspection of Figure 2 it will be noted that the valve 26, spring 30 and sleeve 32 are in alignment with the conduit 24. The conduit 24 has spaces 40 between the flats of the valve 30 and its walls, the length of which is greater than the length of the valve 26 to allow for the passage of oil from the inlet port direct to the outlet port when the valve 26 is lifted from its seat. These spaces 40 will allow the oil to circulate thru the conduit 24 into the conduit 25 and back to the working parts thru the outlet pipe 14 without passing

thru the filter, provided the latter is clogged or refuses to function.

The operation of the device is as follows: Presuming that the filter becomes clogged and refuses to allow the oil to pass therethru the pressure of the oil reaching the intake pipe 13 will raise the valve 26 off its seat, against the pressure of the spring 30, and allow the oil to circulate from the groove 22 thru the conduit 24, spaces 40, conduit 25, outlet plug 18 and back to the working parts thru the outlet pipe 14. The sleeve 32 is normally positioned so that the openings 39 are closed by the plug 35. If it is desired to test the filter to ascertain whether it is in working order the sleeve 32 is turned inwardly by means of a handle 33 causing the head 31 to compress the spring 30 and to hold the valve 26 tightly against its seat 28. This will uncover the ports 39 and if the filter is in working order a quantity of oil will be delivered thru the openings 39 and passage 38 to the outside of the test valve. Should the filter be clogged this will at once be told by the failure of oil to be delivered to the outside of test valve thru the sleeve 32.

I claim:

1. In a by-pass for an oil filter, delivery ports, plugs in said ports, means on said filter to which said plugs are attached, communicating oil passages in said means and plugs, and means to permit the oil to pass from one plug to the other.

2. The structure of claim 1, said first named means comprising studs attached to the filter cover.

3. The structure of claim 1, said passages being concentrically arranged in said plugs and means.

4. The structure of claim 1, and a plurality of radial openings in said plugs communicating with said passages.

5. The structure of claim 1, a plurality of radial openings in said plugs communicated with said plug passages, and an annular groove on said plugs communicating with said radial openings.

6. The structure of claim 1, a plurality of radial openings in said plugs communicating with said plug passages, and an annular groove on said plugs communicating with said radial openings and with said means.

7. In a by-pass construction, inlet and outlet ports in said by-pass, a conduit connecting said ports, a flow control valve in said conduit, resilient means acting on said valve, and a testing device connected to said by-pass construction and adapted to control said resilient means.

8. The invention of claim 7, said testing device adapted to rigidly seat on said valve during the testing operation.

9. In a by-pass construction, a flow control by-pass valve in said construction, and a test

means at said by-pass and adapted to contact with said valve during the testing period.

10. In a by-pass construction for oil filters, a valve in said by-pass construction for controlling the flow of oil, a resilient means for holding the valve on its seat, and a testing device capable of depressing the resilient means and seating itself on the valve to firmly hold it on its seat.

11. The invention of claim 10, said valve being polygonal and relatively long and having a hollow portion, said means seated in said hollow portion.

12. In a by-pass construction, inlet and outlet passages in said construction, a valve in a construction between said passages, and a testing means adapted to rigidly position said valve on its seat to prevent the flow of fluid past said valve during the testing period.

13. In a by-pass for an oil filter, inlet and outlet ports, means for normally causing the flow of oil through the filter, means including an elongated hollow polygonal valve for permitting the oil at times to flow directly through the ports without entering the filter, a spring seated in said hollow to hold said valve on its seat, and a testing device in said by-pass, said device adapted to contact with said valve and compress said spring when testing the filter.

14. In a fitting for connecting the oil purifier in an oil line, a supply channel, a discharge channel, a by-pass leading from said supply to said discharge channel, a relief valve in said by-pass, a test valve in said discharge channel, and means whereby the pressure required to operate said relief valve is increased when said test valve is opened.

15. In a fitting for connecting an oil purifier in an oil line, a supply channel, a discharge channel, a by-pass leading from said supply to said discharge channel, a relief valve in said by-pass, a test valve in said discharge channel, and means operable by said test valve to vary the pressure required to operate said relief valve.

16. In a fitting for connecting an oil purifier in an oil line, a supply channel, a discharge channel, a by-pass leading from said supply to said discharge channel, a relief valve in said by-pass, a test valve in said discharge channel, and means operable by said test valve for applying pressure to said relief valve.

17. In a fitting for connecting an oil purifier in an oil line, a supply channel, a discharge channel, a by-pass leading from said supply to said discharge channel, a relief valve in said by-pass, and a test valve in said discharge channel, said test valve and relief valve being so co-related that the pressure applied to the latter is varied by the former.

18. In a fitting for connecting an oil purifier in an oil line, a supply channel, a dis-

charge channel, a by-pass leading from said supply to said discharge channel, a relief valve in said by-pass, a test valve in said discharge channel, said valve having a portion movable toward and away from said relief valve, and a resilient member interposed between said relief valve and said movable portion.

19. In a by-pass construction, inlet and outlet ports in said by-pass, a conduit connecting said ports, a flow control valve in said conduit, resilient means acting on said valve, and a testing device connected to said by-pass construction and adapted to control said resilient means, said testing device being adapted to increase the tension of the resilient means when testing the filter.

In testimony whereof I affix my signature.
CHARLES W. McKINLEY.
